US0D1060160S

(12) **United States Design Patent** (10) **Patent No.:** **US D1,060,160 S**
(45) **Date of Patent:** **** Feb. 4, 2025**

(54) **ACCELERATOR PEDAL FOR MOTOR VEHICLE**

(71) Applicant: **Dr. Ing. h.c. F. Porsche Aktiengesellschaft**, Stuttgart (DE)

(72) Inventor: **Yuhan Zhang**, Stuttgart (DE)

(73) Assignee: **Dr. Ing. h.c. F. Porsche Aktiengesellschaft** (DE)

(**) Term: **15 Years**

(21) Appl. No.: **29/906,507**

(22) Filed: **Nov. 6, 2023**

(30) **Foreign Application Priority Data**

Jun. 5, 2023 (EM) 015023695-0017

(51) **LOC (15) Cl.** **12-16**

(57) **CLAIM**

The ornamental design for an accelerator pedal for motor vehicle as shown and described.

DESCRIPTION

FIG. 1 is a perspective view of an accelerator pedal for motor vehicle showing my new design;

FIG. 2 is a rear view thereof;

FIG. 3 is a front view thereof;

FIG. 4 is a right view thereof;

FIG. 5 is a left view thereof;

FIG. 6 is an enlarged top view thereof; and,

FIG. 7 is an enlarged bottom view thereof.

The broken lines depict a boundary around the de-emphasized elements, which illustrate portions of the accelerator pedal for motor vehicles which form no part of the claimed design.

1 Claim, 7 Drawing Sheets
